UNITED STATES PATENT OFFICE.

JAMES F. McELROY, OF LANSING, MICHIGAN, ASSIGNOR TO THE CONSOLIDATED CAR HEATING COMPANY, OF WHEELING, WEST VIRGINIA.

WATER-HEATER.

SPECIFICATION forming part of Letters Patent No. 435,075, dated August 26, 1890.

Application filed March 25, 1889. Serial No. 304,720. (No model.)

To all whom it may concern:

Be it known that I, JAMES F. McELROY, a citizen of the United States, residing at Lansing, in the county of Ingham and State of Michigan, have invented certain new and useful Improvements in Water-Heaters, of which the following is a specification, reference being had therein to the accompanying drawings.

10 This invention relates to new and useful improvements in water-heaters, and the invention is especially designed for use in connection with a hot-water-circulating system of piping of the ordinary construction—such as used in house or car heating—consisting of piping or radiators provided with a suitable expansion-drum.

15 The invention consists in the peculiar construction and arrangement of the steam-heater for such a system of piping, whereby water may be heated noiselessly by commingling steam therewith, and at the same time present the smallest possible friction to the free circulation of the water; and the invention further consists in the peculiar construction, arrangement, and combination of the various parts, all as more fully hereinafter described.

20 In the drawings which accompany this specification, Figure 1 shows a perspective view of the hot-water-circulating apparatus as used in a car to which my heater is attached. Fig. 2 is a vertical central section thereof. Fig. 3 is a plan view of the steam-distributing nozzle.

25 A represents a stove or heater usually found in cars provided with this class of circulating apparatus.

B is the train-pipe, designed to carry the steam from the locomotive under the cars.

30 C is the branch pipe for bringing the steam into the steam-heater, and D is the steam-heater, which is preferably arranged in the direct line of the circulating-pipes, and in this case it is shown in the riser G between the stove and the expansion-drum F.

45 G' is the outgoing-pipe from the expansion-drum. J are the circulating or radiating coils in the car. A suitable valve a is placed in the steam-supply pipe to control the admis-

sion of steam into the steam-heater, and the check-valve b is arranged between the valve a and the heater, as is usually applied in such cases. An overflow-pipe E extends into the expansion-drum to a suitable height to carry off the surplus water entering through continued admission of steam.

55 My heater consists of the upper casting c, the central or main part d, and the lower part e. The upper part c consists of the casting or pipe provided at its lower end with a suitable screw-thread adapted to enter a screw-threaded aperture in the top of the main part d, and at its other end with the interior screw-thread to receive the exit of the circulating-pipe G. On its side it is provided with a suitable internally-threaded aperture adapted to receive the steam-inlet pipe. A bend is preferably cast integral into the upper casting and interiorly screw-threaded to receive the steam-pipe g, which at its lower end has secured to it the perforated nozzle h. The main part or body of the heater preferably consists of a pear-shaped vessel, provided at its upper end with the aperture to receive the upper part and at its lower end the screw-threaded aperture to receive the lower part e. Upon the interior are provided the shoulders i, to which is secured, by suitable screws or otherwise, the depending screen or perforated sheet-metal nozzle l, which is bent downward some distance, as shown. To the upper side of the lower part e is secured the screen or nozzle l, which is bent upward some distance to within close proximity of the nozzle h. The side of the heater is provided with a suitable aperture m, which is closed by a screw-threaded nut n.

60 The steam-nozzle h consists of an 8 or S shaped casting o, provided on its upper side, in the middle, with the screw-threaded boss, whereby it may be readily secured to the pipe g. The upper face of the 8-shaped figure is provided with the inclines p and q. The hollow bars r are placed across the openings of the 8-shaped figure, as shown, and the whole upper surface of the nozzle is suitably perforated. The perforations in the inclined sides p and q are preferably so arranged as to discharge the steam in the direction at right angles to

70 75 80 85 90 95 100

the plane of their surfaces. Additional wings *t* may be secured to the nozzle if it is desired to increase the perforated surface.

Within the space between the upper and lower screens *k* and *l*, I preferably arrange shot or gravel, whereby the commingling of the steam and water is noiselessly accomplished in the well-known manner.

A heater thus constructed and arranged is adapted to operate as follows: Steam being turned into the pipe *B* and the valve *a* being opened, steam is admitted into the heater through the pipe *g*, thence into the nozzle, where it is distributed around the 8-shaped figure and the connecting-arms, and is discharged through the perforations into the water which is within the heater between the screens. This at once heats and circulates the water.

The peculiar construction of the upper and lower screens, whereby at their central portion they approximate very closely to the steam-nozzle, together with the peculiar shape of the steam-nozzle, whereby an open passage-way is provided by the loops in the 8-shaped figure, allow of the circulation by the most direct route through the commingler and with the least possible friction to the passage of the water. At the same time a sufficient quantity of the noise-deterring medium is arranged around the steam-nozzle, and a large area is obtained in a small space for the ingress and egress of the heated water through the screens. Should it be desired to operate the device through the medium of a stove, the advantage of this construction will be readily perceived, as no force is obtained for the circulation of the hot water, except the difference in gravity between the water heated in the stove and that without. In this use the smallest possible obstruction must be provided to the free passage of the water, in order to obtain the full benefit. In the use of the stove it will be seen that the close proximity of the upper and lower screens, together with the central aperture in the steam-nozzle in the direct line between the ends of the commingler, permits of the circulation with the least possible obstruction to the circulation under any circumstances. It is obvious that the same results may be obtained by having the steam-pipe enter from below or through the side of the main chamber.

What I claim as my invention is—

1. A water-heater consisting of a drum provided with inlet and exit openings substantially in line, a steam-supply pipe entering said drum, connecting with a steam-nozzle provided with perforations on one side only and arranged in the line of water-circulation, a porous medium around said nozzle, and the screens *k* and *l*, substantially as described. 55

2. In a water-heater, the combination, with the casing, of screens inclosing a porous medium, an open-figured steam-nozzle perforated on one side only and located in the line of circulation between said screens, substantially as described. 60

3. In a water-heater, the combination, with the casing, of semi-globular screens arranged with their convex faces toward each other, whereby they approach most nearly in the line of water-circulation, and the steam-supply pipe and nozzle perforated on one side only between the screens and surrounded by a porous medium, the parts being arranged to operate substantially as described. 70

4. In a water-heater, the combination, with the casing, of the semi-globular screens arranged with their convex faces toward each other, whereby they approach most nearly in the line of water-circulation, and the steam-supply pipe and nozzle perforated on one side only arranged between said screens, substantially as described. 75

5. The combination, with the casing and the screens *k* *l* therein, as shown, of the substantially 8-shaped steam-nozzle arranged between said screens and perforated upon one side only, and a porous medium surrounding 90 said nozzle, substantially as described. 85

6. In a water-heater, the combination, with the casing and the screens *k* and *l* therein, of the steam-nozzle perforated upon one side only and arranged between said screens, the 95 perforated wings *t*, and the porous medium surrounding said nozzle and wings, substantially as and for the purpose specified.

In testimony whereof I affix my signature, in presence of two witnesses, this 4th day of 100 March, 1889.

JAMES F. McELROY.
